UNITED STATES PATENT OFFICE.

JOHN W. GOODERHAM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 16, 1920. Serial No. 417,421.

To all whom it may concern:

Be it known that I, JOHN W. GOODERHAM, a citizen of the United States, residing at New York, in the county of New York and State of New York, have invented certain new and useful Improvements in Telephone-Exchange Systems, of which the following is a full, clear, concise, and exact description.

10 This invention relates to a telephone exchange system in which connections are established through the medium of mechanical switching devices, and more particularly to means whereby a subscriber in an exchange of this character may establish a connection to a toll operator's position for the purpose of obtaining a connection with a subscriber's line in a distant exchange.

20 In exchanges in which connections in the local area are established by mechanical switching devices without the services of a central office operator, it is necessary to make provision for the establishment of toll connections to distant exchanges. This is ordinarily accomplished by providing a special operator's position in the full mechanical exchange with which subscribers may become connected by dialing a signal digit 0. The operator upon ascertaining the connection desired, then proceeds to extend the connection to a toll operator's position through which the connection is further extended to the distant exchange and thence to the desired subscriber's line. When the originating office is located in an exchange having a plurality of offices, a great saving of apparatus and the employment of a less number of operators is required if the toll operator's position is made common to all of the offices of the exchange. To accomplish this result, however, it is necessary to extend trunks from the special operator's position of all of the offices of the exchange to the toll switching center, and as in large communities, as for example, in New York city, many of the offices may be situated long distances from said switching center, it is necessary to provide efficient trunk lines over which full supervision in both directions may be effected.

25 It is therefore an object of this invention to provide a toll trunk for extending a connection from a special operator's position to a toll operator's position in a toll switching center which affords an efficient talking

path, and permits full supervision in both directions. A further object of the invention is to provide a toll trunk which is so arranged as to be held busy at its outgoing end to prevent seizure by other special operators until after it has been freed for use at its incoming end. A still further object of the invention is to provide means for enabling positive supervision over the toll trunk under all conditions of differences of ground potential prevailing at the respective ends of the trunk. A further object is to prevent differences in ground potential from improperly affecting apparatus connected to a line at separated points.

30 These and other objects of the invention will be more readily understood by reference to the accompanying drawings in which—

35 Figs. 1, 2 and 3 taken together with Fig. 2 placed at the right of Fig. 1 and Fig. 3 placed at the right of Fig. 2 show so much of a telephone system as is necessary for an understanding of the invention. Fig. 1 shows a calling subscriber's line A and a line switch 100 individual to the subscriber's line, a selector switch 101 and a trunk circuit 102 by means of which a calling subscriber may extend a connection to a jack at a special operator's position; Fig. 2 shows so much of the circuits of the special operator's position and the selector switch associated therewith as are necessary for a comprehension of the invention; and Fig. 3 shows a toll trunk comprising the novel feature of this invention a toll operator's cord circuit 30 for connection with the distant incoming end of the trunk line, a toll line extending to a distant exchange and the substation circuits of a subscriber's line B terminating in said distant exchange.

40 It will be assumed for convenience in disclosing the invention that the subscriber's line A terminates in a full mechanical office X of the general type disclosed in the Patent 1,395,977 to F. A. Stearn and F. J. Scudder issued November 1, 1921, that the called subscriber's line B terminates in an office Z of a distant exchange and that a toll connection is to be established between the offices X and Z through the toll switching center 45 Y of the same exchange as office X.

45 In general, the system functions in the following manner: The subscriber A desiring a connection with the line of subscriber B in the distant office Z, removes

his receiver from its switchhook and through the operation of the line switch 100 becomes connected to a trunk line terminating in a district selector 101. The subscriber then proceeds to dial digit 0, and through the operation of the full mechanical sender associated with the selector 101 in the manner disclosed in the aforesaid mentioned patent, obtains a connection with a trunk circuit 102 extending to a special operator's position (Fig. 2). The special operator upon answering the call ascertains the number and exchange designation of the desired line, and proceeds to set up upon the key-board of the sender associated with her position such a routing as will set the district selector switch 222 upon the terminals of an idle trunk line extending to a toll operator's position in the toll switching center Y. The toll operator in response to the trunk signal denoting an incoming call, answers by means of her toll cord and then proceeds in the well-known manner to extend the connection over a toll line to the distant exchange in which the connection is further extended to the line of the desired subscriber B.

As the method of extending a connection to the special operator's position shown in Fig. 2 forms no essential part of this invention, the apparatus for effecting such connection has been shown only diagrammatically by a schematic representation of the trunk circuits and of the brushes of the switches 100 and 101, it being understood that this connection may be made in any well-known manner, as for example, as disclosed in the afore-mentioned patent.

The district selector shown at 222 in Fig. 2 is of the general type disclosed in the patent to Craft and Reynolds No. 1,123,696 issued January 5, 1915. For controlling the circuits associated with this selector switch, an auxiliary switch 200 of the switch type such as disclosed in the patent to Reynolds and Baldwin No. 1,127,808, issued February 9, 1915, is employed. This auxiliary switch comprises a switch shaft carrying a plurality of contact operating cams 201 to 221 inclusive, which in different angular positions effect the closure of the several circuits of the selector switch. Cam 201 is a master cam and opens the contact associated therewith only in the positions indicated by the numerals applied adjacent thereto. The remaining cams close their respective contacts only in the positions indicated by the numerals applied adjacent thereto.

The district selector switch 222 is selectively controlled in its adjustment by an office sender mechanism diagrammatically represented by the relays and circuits with in the dotted rectangle marked "Sender," shown in the lower left-hand corner of Fig.

2. This sender is of the well-known type and since it enters only incidentally into the disclosure of this invention and forms no essential part thereof, the diagrammatic disclosure is thought to be sufficient. The sender may be associated with the cord circuit by means of a sender selector of the well known type, which selector has been represented by the apparatus enclosed in the dotted rectangle marked "Sender selector."

The apparatus disclosed in Fig. 3 for extending a toll connection from the incoming end of the toll trunk at office Y, to the line of a desired subscriber B in office Z, has been represented in a diagrammatic manner since the specific means for extending such a connection is well known in the art and is immaterial to an understanding of this invention.

The various apparatus employed and the general method of operation of the invention having now been described, a detailed description of the method of extending a connection from the line of subscriber A to the line of subscriber B will now be given.

The calling subscriber, upon removing his receiver from the switch hook closes a circuit for starting the line switch 100 in its hunting movement in search of an idle trunk circuit extending to a district selector 101. As soon as an idle district selector 101 has been seized, a central office sender is associated with the trunk circuit terminating in the district selector in the manner fully set forth in the application hereinbefore mentioned. The subscriber then proceeds to dial the digit 0 for adjusting the central office sender to set the district selector upon a trunk circuit 102 extending to a special operator's position in the office X.

As soon as the trunk circuit 102 is seized, a circuit is established for the line relay 103, extending from grounded battery through the right-hand winding of this relay, the inner right-hand armature and back contact of cut-off relay 104, the tip conductor of trunk circuit 102, the winding of a supervisory relay (not shown) associated with district selector 101, and back through the ring conductor of trunk circuit 102, the left-hand armature and back contact of relay 104, thence to ground through the left-hand winding of relay 103. Relay 103 energizes in this circuit and, at its left-hand armature and front contact closes a circuit for the trunk signal lamp 105. At its right-hand armature and front contact, relay 103 closes a circuit extending from grounded battery through the winding of slow-to-release relay 106, which relay upon energizing connects a busy ground potential to the test terminal 107, and the multiples thereof appearing in the banks of all selectors having access to the trunk circuit 102. This circuit

60 65 70 75 80 85 90 95 100 105 110 115 120 125 130

may be traced from ground through the resistance element 108, the armature and front contact of relay 106 and thence to the terminal 107. This circuit is effective for holding 5 switches 100 and 101 in their operated positions until the special operator takes down the connection.

The operator upon noting the illumination of the trunk lamp 105, inserts the plug 10 P of an idle cord circuit of her position in the jack J corresponding to the trunk circuit 102 with which the trunk lamp 105 is associated. A circuit is now established 15 from grounded battery through the winding of sleeve relay 223, over sleeve conductor 224, sleeve contact 109 of plug P, sleeve contact 110 of jack J and thence to ground through the winding of cut-off relay 104. Both relays 223 and 104 energize in this 20 circuit, relay 104 opening the circuit previously traced extending through the windings of relay 103, and at its outer right-hand armature and front contact closing a new circuit for maintaining the relay 106 energized. Relay 106, being slow to release, 25 does not deenergize during the interval in which relay 103 is deenergized before relay 104 has fully attracted its armatures. Sleeve relay 223 of the operator's cord circuit upon energizing, closes a circuit for the listening-in relay 225, which circuit may be traced from grounded battery through the normally closed contacts of the listening-out key LO, winding of relay 225, the lower 30 armature and front contact of relay 223 and thence to ground through the upper contact of sequence switch cam 202 (1 to 1 1/4). Relay 225, upon energizing closes a locking 35 circuit for itself independent of the contact of sequence switch cam 202, extending from grounded battery, through the contacts of listening-out key LO, winding of relay 225, left-hand armature and front contact of this relay, and thence to ground through the 40 winding of relay 226. Relay 226 does not, however, energize in this circuit at this time since its winding is shunted by a direct connection to ground through the lower 45 armature and front contact of sleeve relay 223, and the upper contact of sequence switch cam 202, but will energize, however, as soon as the sequence switch leaves position 1 1/4 as will be explained hereinafter.

Upon the energization of relay 225, energizing circuits for relays 227, 228 and 229 are established, extending from ground through the right-hand armature and front contact of relay 225, thence in parallel 50 through the windings of relays 227 and 228 to grounded battery and through the right-hand winding of relay 229 to grounded battery. Relay 228, upon energizing, closes a circuit extending from grounded battery through the supervisory lamp 230, the lower 55 left-hand contact of sequence switch cam

203 (1 to 2 1/2) and thence to ground through the armature and front contact of relay 228. Relay 227 at its left-hand armature and front contact establishes a circuit for the supervisory lamp 231 extending from 60 grounded battery through the lamp, the lower right-hand contact of sequence switch cam 204, and thence to ground through the left-hand armature and front contact of relay 227. Both supervisory lamps 230 and 231 being now illuminated, the operator is 65 apprised of the fact that the connection has been properly extended to the calling subscriber's line and that the circuits of the district selector 222 in which her cord circuit terminates are proceeding to function in the proper manner. Relay 227, at its right-hand armature and front contact prepares a circuit for the flashing relay 232, which 70 circuit becomes effective later in the progress of the connection and will be described hereinafter. Relay 229, upon energizing, 75 closes a locking circuit for itself, extending from grounded battery through the answering supervisory lamp 233, the armature and front contact of answering supervisory relay 234, which relay became energized over the trunk circuit extending to the calling subscriber's line as soon as the 80 connection was established with the operator's cord circuit, thence to ground through the left-hand armature and front contact and left-hand winding of relay 229. At its right-hand armature and front contact, relay 229 closes a circuit for driving 85 the sequence switch of the district selector 222 out of its normal position 1 into position 2, this circuit extending from grounded battery through the driving magnet of the sequence switch 200, the upper left-hand contact of sequence switch cam 205, and thence to ground at the right-hand armature and front contact of relay 229. As soon as 90 the sequence switch leaves position 1 1/4, the sequence switch cam 202 opens its upper contact thereby removing the shunt from around the relay 226, and this relay then energizes in series with listening-in relay 225 and at its armatures connects the strands 95 of the cord circuit with the operator's set which is indicated at O. T. The operator is now enabled to converse with the calling subscriber and receives from him instructions as to the further extension of the 100 connection.

As soon as the sequence switch 200 reaches position 2, a sender selector switch, diagrammatically represented in the dotted rectangle marked "Sender selector," is started to associate a sending mechanism with the district selector 222. Following the association of a sending mechanism with the district selector, the sequence switch, not shown, but associated with the sender selector advances into position 4, and a circuit is there- 105

110

115

120

125

130

- upon established for advancing the sequence switch of the district selector 222 from position 2 into position 3, this circuit extending from grounded battery, through the winding of the driving magnet of sequence switch 200, the lower right-hand contact of sequence switch cam 205, and thence to ground through the contact of sequence switch cam 235 at the sender selector.
- 10 It having been assumed that the calling subscriber desires a connection with a distant exchange, with which connection must be established over a toll trunk, the operator now depresses routing keys associated with the sending mechanism, for controlling the sending mechanism to set the brushes of the district selector 222 upon a trunk circuit extending to a toll switching center Y, and through the operation of the routing keys, the sequence switch (not shown) but associated with the sending mechanism is driven out of its normal position into position 2.
- 15 With the sequence switch of the sending mechanism in position 2, and the sequence switch of the district selector 222 in position 3, a fundamental circuit is established extending from the line relay 236 of the district selector, through the windings of the stepping relay 237 of the sending mechanism, which may be traced as follows: from grounded battery, through the left-hand winding of line relay 236, the lower left-hand contact of sequence switch cam 206, the upper left-hand contact of sequence switch cam 207, the outer right-hand armature and back contact of relay 238, through the windings of stepping relay 237 of the sending mechanism, the armature and back contact of relay 239, and thence to ground through the contact of sequence switch cam 240 of the sequence switch of the sending mechanism. Relays 236 and 237 both energize in this circuit, relay 236 closing a circuit for driving the sequence switch 200 out of position 3 and into position 4. This circuit may be traced from grounded battery, the winding of the driving magnet of sequence switch 200, the left-hand contacts of sequence switch cam 208, and thence to ground through the right-hand armature and front contact of relay 236. As soon as the sequence switch leaves position 3, the initial energizing circuit of relay 236 is opened at the lower left-hand contact of sequence switch cam 206 but the line relay remains locked up to the fundamental circuit, through its left-hand winding, its inner left-hand armature and front contact and thence to the fundamental circuit, through the upper left-hand contact of sequence switch cam 206, which contact remains closed through positions 1 to 6. The closure of the outer left-hand armature with its front contact is without effect at this time.

At the sending mechanism, the energization of the stepping relay 237 functions in the usual manner.

When the sequence switch 200 reaches position 4, a circuit is established for the up-drive magnet 241 of the district selector 222 for driving the shaft 242 of the selector upwardly in its brush selection movement through the operation of updrive roller 274. This circuit may be traced from grounded battery through the winding of the up-drive magnet 241, the upper right-hand and lower left-hand contacts of sequence switch cam 208, and thence to ground at the right-hand armature and front contact of relay 236. During the upward movement of the switch shaft, a direct connection to ground in shunt of the winding of the stepping relay 237 of the sending mechanism, is intermittently established over the following circuit: from ground, through the lower left-hand contact of sequence switch cam 202 (9 to 7), shaft wiper 243, the brush selection segment 244 of the commutator 245 and thence to a junction point in the fundamental circuit between the windings of relays 236 and 237 at the lower right-hand contact of sequence switch cam 206 closed in position $3\frac{3}{4}$ to 4. Upon each connection of the shunt circuit, as previously traced, the stepping relay 237 of the sending mechanism deenergizes to operate the counting relays of the sending mechanism in the well-known manner. When the counting relays of the sending mechanism have been satisfied, the 0' counting relay energizes in parallel with relay 239 in the well-known manner. Counting relay 0' causes the sequence switch of the sending mechanism to be advanced to position 4, and relay 239 at its armature and back contact opens the fundamental circuit, previously traced, through the windings of relays 236 and 237. Upon the opening of the fundamental circuit, relay 236 deenergizes, opening at its right-hand armature and front contact the circuit previously traced extending through the winding of the up-drive magnet 241, thereby causing the switch shaft to be arrested in its upward movement with a certain one of its brush sets positioned in such a manner with respect to the tripping spindle 246 as to cause such set of brushes to be tripped when the tripping magnet 247 is later energized and the switch shaft is again driven upwardly. At its right-hand armature and back contact, relay 236 closes a circuit for advancing the sequence switch 200 out of position 4 and into position 5, this circuit extending from grounded battery through the winding of the driving magnet of the sequence switch 200, the lower contact of sequence switch cam 209 and thence to ground at the back contact and right-hand armature of relay 236. A circuit is now

established for the trip magnet 247, extending from grounded battery through the winding of trip magnet 247, and thence to ground through the right-hand contact of sequence switch cam 210.

With the sequence switch of the sending mechanism in position 4, and the sequence switch 200 in position 5, the fundamental circuit extending through the windings of relays 236 and 237, is again established and these relays both energize as previously described. Relay 236, upon energizing, closes a circuit extending from grounded battery, through the winding of the driving magnet of sequence switch 200, the left-hand contacts of sequence switch cam 208, and thence to ground at the right-hand armature and front contact 236, for driving sequence switch 200 out of position 5 and into position 6. Upon leaving position 5, the initial energizing circuit of relay 236 extending over the fundamental circuit, is opened at the lower left-hand contact of sequence switch cam 206, but the relay is maintained energized over its left-hand winding, its inner left-hand armature and front contact and through the upper left-hand contact of sequence switch cam 206 and thence over the fundamental circuit. With the sequence switch in position 6, the circuit of the up-drive magnet 241 is again established over the circuit previously traced, and the switch shaft is now driven upwardly in its group selection movement by the updrive roller 274. During this upward movement of the switch shaft, a ground is connected intermittently to the fundamental circuit between the windings of relays 236 and 237 over a circuit which may be traced from ground at the lower left-hand contact of sequence switch cam 202, shaft wiper 276, the group selection segment 248 of commutator 245, and thence to the fundamental circuit through the upper right-hand contact of sequence switch cam 206 (5 $\frac{3}{4}$ to 6). In response to the upward movement of the switch shaft, the stepping relay 237 of the sender is intermittently operated in the well-known manner until the counting relays of the sending mechanism have counted down in accordance with their setting as determined by the routing registered by the operator. When the 0' counting relay energizes, the sequence switch of the sending mechanism is advanced from position 4 into position 6 in the well-known manner, and relay 239 which energizes in parallel with the 0' counting relay, opens the fundamental circuit at its armature and back contact. In response to the opening of the fundamental circuit, relay 236 deenergizes, opening at its right-hand armature and front contact, the circuit previously traced extending through the winding of up-drive magnet 241 to arrest the tripped set of brushes

of the selector switch on the lowermost set of terminals of the selected group of bank terminals. At its right-hand armature and back contact, relay 236 closes the circuit previously traced for driving the sequence switch 200 out of position 6 and into position 7. Upon reaching position 7, a circuit is established for the relay 236 which may be traced from grounded battery through the right-hand winding of relay 236, and thence to ground through the lower contacts of sequence switch cam 211. Relay 236, energizing in this circuit closes a circuit for driving the sequence switch 200 out of position 7 into position 8, this circuit extending from grounded battery through the driving magnet of sequence switch 200, the left-hand contacts of sequence switch cam 208 and thence to ground at the armature of relay 236. As soon as the sequence switch leaves position 7 $\frac{1}{4}$ the energizing circuit of relay 236 is opened at the lower right-hand contact of sequence switch cam 211. Relay 236 however, remains energized over a locking circuit extending through its left-hand winding, its inner left-hand armature and front contact, the upper contacts of sequence switch cam 212, the outer left-hand armature and front contact of relay 236, the upper right-hand contact of sequence switch cam 221, test brush 249 and thence to the lowermost test terminal 250 of the group of trunk lines to which the selected brush set has been moved if the first trunk line of the group is busy. If this first trunk line, however, is at the time idle, the locking circuit for relay 236 is not established and relay 236 immediately deenergizes thereby preventing the establishment of a circuit for the up-drive magnet 241 and the operation of the switch in its trunk hunting movement when the sequence switch reaches position 8. Assuming, however, that the first trunk line of the group is busy, relay 236, remains locked up after the sequence switch leaves position 7 and a circuit is thereupon established for the up-drive magnet 241, which circuit may be traced from grounded battery, through the winding of magnet 241, the upper right-hand and lower left-hand contacts of sequence switch cam 208, and thence to ground at the right-hand armature and front contact of relay 236. When the test brush 249 engages the test terminal of an idle trunk circuit, which in the case assumed is the terminal 251, the locking circuit of relay 236 is opened and the relay deenergizes thereby opening the circuit of the up-drive magnet 241. Relay 236, however, does not deenergize until the brush set has become properly centered upon the terminals of the selected idle trunk, since relay 236 is held energized over a circuit extending from grounded battery, through its right-hand winding, the lower left-hand and

upper right-hand contacts of sequence switch cam 211, the centering segment 252 of the commutator 245, switch shaft wiper 253, the lower contacts of sequence switch cam 208 and thence to ground at the armature and front contact of relay 236. This centering locking circuit is opened as soon as the wiper 253 engages an insulating portion of segment 252 corresponding to the position of switch shaft 242 in which the brush set is properly centered on the selected set of trunk terminals.

Relay 236, upon deenergizing in addition to opening the circuit of up-drive magnet 241, closes a circuit extending from grounded battery, through the winding of the driving magnet of sequence switch 200, the lower left-hand contact of sequence switch cam 209 and thence to ground, through the right-hand armature and back contact of relay 236, for driving the sequence switch out of position 8 and into position 9. Relay 236 now closes a circuit for placing ground potential upon the test brush 249 of the selector switch to mark the selected trunk circuit as busy to other selector switches which have access thereto, this circuit extending from ground, through the upper left-hand contact of sequence switch cam 210 (7 to 9), the inner left-hand armature and back contact of relay 236, the left-hand contacts of sequence switch cam 212, overflow segment 254 of commutator 245, shaft wiper 255 and thence to test brush 249. The selected trunk circuit is also held busy by ground potential connected to the test brush 249 from the left-hand armature and back contact of relay 238, thence through the lower contacts of sequence switch cam 212, and over the circuit previously traced, this ground potential being maintained on the test brush 249 through position 11 of the sequence switch.

During the setting of the selector switch 222, supervisory lamp 230 was maintained illuminated over a circuit extending from grounded battery, through lamp 230, the upper left-hand contact of sequence switch cam 203 and thence to ground at the left-hand armature and back contact of relay 256. Lamp 231 was maintained illuminated over a circuit extending from grounded battery, through lamp 231 and thence to ground through the lower left-hand contact of sequence switch cam 204, the illumination of these lamps signifying to the operator that selection is proceeding.

As soon as the sequence switch 200 reaches position 9 since, at this time, the sequence switch of the sender selector is in position 8 following the registration of the routing of the connection upon the sending mechanism, a circuit is established for advancing the sequence switch 200 out of position 9 and into position 10, this circuit extending from grounded battery, the winding of the driving

magnet of sequence switch 200, the contacts of sequence switch cam 213 (9), contact of sequence switch cam 257 of the sequence switch (not shown) of the sender selector, and thence to ground at sequence switch cam 240 of the sequence switch associated with the sending mechanism. If the trunk circuit which has been selected is in proper condition for extending the connection, sequence switch of the sending mechanism is now advanced in the well-known manner into position 7, and a circuit is then closed for advancing the sequence switch 200 into position 11, this circuit extending from grounded battery, through the winding of the driving magnet of sequence switch 200, the lower right-hand contact of sequence switch cam 205, and thence to ground at the left-hand contact of sequence switch cam 258. As soon as the sequence switch 200 leaves position 10 1/4, the circuit of supervisory lamp 231 is opened at sequence switch cam 204, and since now lamp 230 is illuminated and lamp 231 is dark, the operator is apprised of the fact that selection has been completed.

When the sequence switch reaches position 11, a fundamental circuit is established extending through the windings of relays 236 and 237 which may be traced from grounded battery, through the left-hand winding of relay 236, the lower left-hand contact of sequence switch cam 206, the upper left-hand contact of sequence switch cam 207, the outer-right-hand armature and back contact of relay 238, windings of relay 237, armature and back contact of relay 239 and thence to ground through the contacts of sequence switch cam 259. Relay 236, energizing in this circuit, closes at its right-hand armature and front contact, a circuit extending through the left-hand contacts of sequence switch cam 208 for driving the sequence switch 200 out of position 11. Relay 236 is maintained energized after the sequence switch leaves position 11 and opens the lower left-hand contacts of sequence switch cam 206, over a circuit extending through its left-hand winding, its inner left-hand armature and front contact and thence through the upper left-hand contact of sequence switch cam 206 and over the fundamental circuit as previously traced. The sequence switch in passing position 11 1/8 establishes a direct connection to ground between the windings of relays 236 and 237, this circuit extending from ground, through the lower contact of sequence switch cam 207 and thence to the fundamental circuit at the upper left-hand contact of sequence switch cam 206. In response to the connection of direct ground to the fundamental circuit, the stepping relay 237 of the sending mechanism deenergizes, and in the well-known manner controls the energization of one of

the counting relays associated with the sending mechanism. As the sequence switch 200 passes positions $12\frac{5}{8}$, $13\frac{5}{8}$, and $14\frac{5}{8}$, the stepping relay 237 of the sending mechanism is further intermittently deenergized and if in the case assumed, the sending mechanism has been so adjusted by the depression of the routing keys as to cause the 0' counting relay to be energized only when the sequence switch 200 has passed position $14\frac{5}{8}$, then when this position is passed, the 0' counting relay energizes in parallel with relay 239 and in the well-known manner causes the sequence switch associated with the sending mechanism to be advanced out of position 7 and in the present case, to be restored to normal. Relay 239, which energized in parallel with relay 0', opens the fundamental circuit thereby causing relay 236 to become deenergized to open the driving circuit of the sequence switch 200 to arrest the sequence switch in position 15. The advance of the sequence switch 200 under the control of the sending mechanism, is for the purpose of connecting the secondary windings of repeating coil 260 with the brushes of the selector switch in different ways in accordance with the class of connection being established, for affording the most efficient talking path. For this purpose the right-hand windings of the repeating coil 260 may be divided into sections and placed under the control of the district sequence switch, as fully disclosed in the aforesaid patent issued to F. A. Stearn and F. J. Scudder.

With the sequence switch of the cord circuit in position 15, a circuit is established for the flashing relay 232, which may be traced from grounded battery through the winding of relay 232, the right-hand armature and front contact of relay 227, and thence to ground through the upper left-hand and also right-hand contacts of sequence switch cam 221. Relay 232, upon energizing, opens at the normal contacts of its armatures, a direct connection between the right-hand windings of the repeating coil 260 and the contacts of cams 214 and 215, and interposes in this connection the normally closed contacts of the operator's flashing key 277. After leaving position 11, the circuit previously traced extending from the left-hand armature and back contact of relay 238 to the brush 249 for holding the selected toll trunk busy, is opened at the lower right-hand contact of sequence switch cam 212 and the selected trunk circuit is then held busy through position $15\frac{1}{2}$ of the sequence switch over a circuit extending from brush 249 through shaft wiper 255, overflow segment 254 and to ground through the upper left-hand and lower right hand contacts of sequence switch cam 211.

In position 15 of the sequence switch, a

circuit is established for the line relay 300 associated with the outgoing end of the selected toll trunk circuit which may be traced from grounded battery through the right hand winding of relay 300, the innermost upper 70 armature and back contact of switching relay 301, the tip conductor 302 of the selected trunk circuit, bank terminal 261 and brush 262 of selector 222, the contact of sequence switch cam 214, the upper armature 75 and front contact of flashing relay 232, the normally closed right hand contacts of flashing key 277, the upper make contacts associated with the upper armature of relay 232, the upper right-hand winding of repeating 80 coil 260, the contact of sequence switch cam 216 (14 $\frac{3}{4}$ to 15), the winding of polarized supervisory relay 263 the contact of sequence switch cam 217, the lower right hand winding of repeating coil 260, the make contacts 85 associated with the lower armature of relay 232, the normally closed left-hand contacts of flashing key 277, the lower armature and front contact of relay 232, contact of sequence switch cam 215, brush 264 of selector 90 222, terminal 265, ring conductor 303 of the selected toll trunk circuit, the lower innermost armature and back contact of switching relay 301 and thence to ground through the left-hand winding of relay 300. Relay 95 263 closes a circuit which may be traced from grounded battery, through the winding of relay 256, right hand armature and back contact of relay 266 and thence to ground through the armature and front contact of relay 263. Relay 256, upon energizing closes a locking circuit for itself extending through its winding, its inner right hand armature and front contact and thence to ground, through the lower right hand contact of sequence switch cam 202 (2 to 18). At its left hand armature and front contact, relay 256 establishes a new circuit for lamp 230 which may be traced from grounded battery through the lamp, the upper right 105 hand contact of sequence switch cam 203, the left-hand armature and back contact of relay 266 and thence to ground through the left hand armature and front contact of relay 256, thus placing the lamp 230 under the joint control of relays 256 and 266. At its outer armature and front contact, relay 256 completes a circuit for relay 266 which circuit becomes effective as soon as supervisory 110 relay 263 deenergizes upon the response of the toll operator at the switching center Y.

Relay 300 associated with the incoming end of the toll trunk upon energizing, establishes a circuit for sleeve relay 304 of the toll trunk, which circuit may be traced from grounded battery through the winding of relay 304, the armature and front contact of relay 300, sleeve conductor 305, bank terminal 251 and test brush 249 of selector 125 switch 222, and thence over the circuit pre- 130

viously traced to ground at the lower right ground through the winding of relay 316. hand contact of sequence switch cam 211. Relay 316, upon energizing, closes a circuit. Relay 304, upon energizing in this circuit, for the trunk lamp 318 associated with the closes a circuit extending from grounded jack J' in which the selected toll trunk 70 battery, through the winding of slow-to-release relay 306 and to ground at the left. The toll operator at position O in the toll hand armature and front contact of relay switching center Y, in response to the illumination of the trunk lamp 318 inserts front contact, relay 304 establishes a lock-the plug P' of one of the toll cord circuits 75 10 circuit for itself extending directly to at her position in the jack J' of the toll the sleeve conductor 305 independent of the trunk with which the illuminated lamp 318 armatures of line relay 300, and at its right-hand armature and inner front contact is associated, whereupon a circuit is established which may be traced from grounded hand armature and inner front contact established which may be traced from grounded 15 establishes a circuit for switching relay 301, battery through the winding of the marginal sleeve relay 319 of the cord circuit, 80 which may be traced from grounded battery through the winding of this relay through the sleeve contact 320 of the plug and ring conductors 302 and 303 of the 100 previously traced extending through the windings of relay 314, and at its left-hand armature and front contacts connects the flash-to-release relay 317 which upon energizing, 85 to the conductors 307 and 308 respectively connects the flash-to-release relay 317 which upon energizing, 90 of the outgoing end of the trunk circuit extending supervisory relay 322 with the conductors 307 and 308 of the toll trunk. At 95 20 At its outermost armatures and back contacts, relay 301 disconnects the conductors 309 and 310, which conductors are normally connected to the trunk conductors 307 and 308 respectively. 105 25 Slow-to-release relay 306, upon energizing, front contact, relay 317 establishes a locking circuit for relay 311, which circuit may be traced from grounded battery and front contact of relay 314 which locking 110 30 through the winding of relay 311 and the circuit becomes effective to hold the relay 311 upon energizing, connects the windings of relay 312 and of differential relay 313 to 115 35 the conductors 309 and 310 for a purpose to be described hereinafter. Due to the substitution of the direct bridge 40 As soon as relay 301 has joined the tip conductors of the incoming and outgoing ends of the toll trunk, a circuit is established for the line relay 314 associated with the distant end of the trunk circuit. The circuit of this relay may be traced from 120 45 conductor 308, the innermost lower armature and front contact of switching relay 301, conductor 303, and thence over the circuit previously traced, through the winding of relay 314, the innermost upper armature and front contact of relay 301, conductor 302, the innermost upper armature and front contact of relay 301, conductor 307, the outer left hand armature and back contact of relay 315 and thence to ground. 125 50 Relay 314, energizing in this circuit, establishes a circuit for the lamp relay 316 which circuit extends from grounded battery through the armature and front contact of relay 314, the armature and back contact of slow-to-release relay 317 and thence to ground at the left hand armature 130 55 60 65

circuit becomes effective upon the subsequent energization of polarized supervisory relay 263 when the distant toll operator disconnects from the toll trunk either for the purpose of flashing the special operator or for giving the special operator a disconnect signal.

At the toll switching center, marginal relay 319 does not energize and therefore no circuit is closed for the supervisory lamp 323. The toll operator, after establishing a connection with the toll trunk, throws her listening key 324 to connect her headset with the cord circuit which she has employed and over the connection established with the special operator (Fig. 2) obtains instructions for further extending the connection. It having been assumed that a connection is desired with the subscriber's line B which terminates in an office Z of a distant exchange, the toll operator will obtain the assignment of a trunk circuit extending to the desired exchange and will then insert the plug P² of the cord circuit in the jack J² of the assigned trunk, whereupon a circuit will be established from ground through the sleeve contacts of the plug and jack, winding of relay 325, resistance 326, and thence to grounded battery. The energization of relay 325 joins the tip of the plug P² with the tip strand of the operator's cord circuit.

Following the extinguishing of supervisory lamp 230 denoting that the distant toll operator has answered the call, the special operator may listen out on the connection by depressing the listening-out key LO opening the locking circuit of listening-in relay 225 which deenergizes and opens the circuits of relays 227, 228 and 229. Relays 227, 228 and 229 deenergize when the locking circuit of relay 225 is opened. Relay 226 which is also energized in this locking circuit also deenergizes disconnecting the operator's set from the answering end of the cord circuit and connecting the answering end of the cord circuit directly to the left-hand windings of the repeating coil 260. If the operator wishes to listen in again on a connection, she depresses listening-in key LI which closes a circuit extending from grounded battery, through the normally closed contact of listening-out key LO, the winding of relay 225, the lower armature and front contact of relay 223, contacts of listening-in key LI to ground at the lower contact of the sequence switch cam 202. Relay 225 energizes in this circuit closing a locking circuit for itself extending through its left hand armature and front contact and to ground as previously described, through the winding of relay 226, relay 226 thereupon reconnects the operator's headset to the cord circuit.

If the operator wishes to flash the toll

operator in the distant toll switching center, she throws the flashing key 277 to connect grounded battery and ground to the tip and ring strands of the out-going end of her cord circuit for operating the relay 322 at the distant end of the toll trunk 307 and 308. The energizing circuit of relay 322 may be traced from grounded battery, through resistance element 268, through the right hand contact of key 277, the upper armature and front contact of flashing relay 232, contact of sequence switch cam 214, selector switch brush 262, bank terminal 261, trunk conductor 302, the innermost upper armature of switching relay 301 and its front contact, trunk conductor 307, the outer left hand armature and front contact of relay 315, the winding of flashing supervisory relay 322, the inner left hand armature and front contact of relay 315, trunk conductor 308, the innermost lower armature and front contact of relay 301, trunk conductor 303, bank terminal 265, switch brush 264, contact of sequence switch cam 215, lower armature and front contact of flashing relay 232, the left hand contact of key 277 and thence to ground through the resistance element 269. Relay 322, in response to each operation of the flashing key 277, attracts its armature thereby connecting the right hand winding of relay 315 in parallel with the left hand winding of this relay thereby reducing the resistance of the sleeve circuit extending through the winding of supervisory relay 319 of the toll operator's cord circuit. In response to the reduction of the resistance of the sleeve circuit, relay 319 energizes and attracts its armature to operate the supervisory lamp 323. The lamp 323, therefore, flashes in response to each operation of the flashing key 277 to attract the attention of the toll operator.

If the toll operator desires to flash the special operator, she will temporarily withdraw plug P' from the jack J' thereby opening the circuit through sleeve relay 315. Relay 315, upon deenergizing, disconnects the bridged relay 322 from the strands of the trunk circuit and connects the windings of relay 314 and bridged battery to the conductors of the trunk. In response to the connection of bridged battery across the conductors of the trunk circuit, the polarized supervisory relay 263 at the special operator's cord circuit becomes energized to close a circuit extending from grounded battery, through the supervisory lamp 231, armature and front contact of relay 266 and to ground at the armature and front contact of relay 263. Thus in response to each withdrawal of the plug P' from the jack J', the lamp 231 at the special operator's cord circuit, flashes to give the special operator a recall signal.

Following the extension of the connection

to the trunk line terminating at the toll operator's position in jack J² and extending to the distant exchange, the connection is extended in the well-known manner at such 5 distant exchange to the office Z in which the desired line B terminates and the subscriber on line B is called in the usual manner.

Upon the termination of the conversation between the subscriber A in office X and the 10 subscriber B in office Z, the calling subscriber restores his receiver to its switch-hook thereby opening the circuit previously traced extending through the supervisory relay 234. This relay thereupon deenergizes, opening the locking circuit previously 15 traced, through the left hand winding of relay 229, and connects the supervisory lamp 233 in a circuit extending from grounded battery through the lamp 233, the 20 armature and back contact of relay 234 and thence to ground through the lower contacts of sequence switch cam 210. The operator, noting the illumination of lamp 233, then 25 proceeds to take down the connection by withdrawing plug P from the jack J. When the plug is withdrawn from the jack, the circuit existing through the windings of cut-off relay 104 of the trunk 102 and the sleeve relay 223 of the cord circuit, is 30 opened and the relays deenergize. Since, at this time, relay 229 is deenergized, a circuit is established for relay 238 which may be traced from grounded battery, through the winding of relay 238, the left 35 hand contact of sequence switch cam 219, the upper armature and back contact of sleeve relay 223 and the right hand armature and back contact of relay 229 to ground. Relay 238, energizes in this circuit and at 40 its inner right hand armature and front contact, closes a locking circuit for itself extending to ground at the lower right hand contact of sequence switch cam 202. At its left hand armature and front contact, relay 45 238 closes a circuit for driving the sequence switch 200 out of the talking position 15 and into position 17, this circuit may be traced from grounded battery through the winding of the driving magnet of sequence switch 200, the lower right hand contact of sequence switch cam 220 and thence to ground at the left hand armature and front contact of relay 238. Upon 50 reaching position 17, a circuit is established for advancing the sequence switch into position 18, which circuit may be traced from grounded battery, through the winding of the driving magnet of sequence switch 200, the upper right hand contact of sequence switch cam 219, the upper armature and back contact of sleeve relay 223 and thence to ground at the right hand armature and back contact of relay 229.

With the sequence switch in position 18, a

circuit is established for the down-drive 65 magnet 270 of the selector switch 222, which circuit may be traced from grounded battery through the winding of magnet 270 and thence to ground through the upper contacts of sequence switch cam 220. The energization of down-drive magnet 270 in the well-known manner through the operation 70 of the down-drive roller 275 drives the switch shaft 242 downwardly into its normal position. When the switch shaft reaches its normal position, a circuit is established for driving the sequence switch out of position 18 and into its normal position, this circuit may be traced from grounded battery, through the winding of the magnet of sequence switch 200, the upper right hand contact of sequence switch cam 205, normal commutator segment 271, shaft wiper 276 and thence to ground through the lower left hand contact of sequence switch cam 202. The selector switch 222 and the sequence switch associated therewith are now in normal position.

At the trunk circuit 102 upon the deenergization of relay 104, the circuit of relay 106 is opened at the outer right hand armature and front contact of relay 104, and since at this time there is no energizing circuit for line relay 103, the calling subscriber having restored his receiver to the switch hook, relay 106 disconnects ground potential from the test terminal 107 causing thereby the release of selector switch 101, and of line switch 100. All the apparatus in the originating office X is now in normal position.

Upon the restoration of the district selector switch 222, the sleeve circuit over which relay 304 of the toll trunk was held energized is opened at sequence switch cam 211 and this relay deenergizes thereby opening the circuit of switching relay 301, which upon deenergizing opens the talking conductors of the trunk circuit and at its outermost armatures connects the windings of relays 312 and 313 to the conductors 307 and 308 of the trunk circuit. Relay 312 now energizes over the trunk circuit in series with relay 322, and at its armature and front contact, closes a holding circuit for the slow-to-release relay 306 which may be traced from grounded battery, through the winding of relay 306, the armature and back contact of relay 313, the armature and front contact of relay 312 and thence to ground through the armature and front contact of relay 306. Relay 306 is thus maintained energized after the initial energizing circuit is opened upon the deenergization of sleeve relay 304 to maintain relay 311 energized and busy ground potential connected to conductor 305 until the distant toll operator disconnects. The energization of

relay 322 in series with relay 312 connects the right hand winding of relay 315 in parallel with the left hand winding of this relay, as previously described, thereby operating the supervisory lamp 323 associated with the toll operator's cord circuit to give the toll operator a disconnect signal.

The toll operator in response to the disconnect signal withdraws the plugs of her cord circuit from the jacks J^1 and J^2 . The withdrawal of answering plug P^1 opens the circuit extending through the windings of cut-off relay 315 and through the winding of supervisory relay 319, and these relays deenergize, relay 319 extinguishing the signal lamp 323, and relay 315 disconnecting the winding of relay 322 from the conductors of the trunk circuit and connecting the windings of relay 314 in place thereof. The circuit through the right hand winding of relay 314 may now be traced from grounded battery, the right hand winding of this relay, the inner left hand armature and back contact of relay 315, conductor 308, the lowermost armature and back contact of relay 301, conductor 309, the inner left hand armature and front contact of relay 311, the left hand winding of relay 312, the left hand winding of differential relay 313 and thence to grounded battery. The circuit through the left hand winding of relay 314 may be traced from ground through the left hand winding of this relay, the left hand armature and back contact of relay 315, conductor 307, the uppermost armature and back contact of relay 301, conductor 310, the outer right hand armature and front contact of relay 311 and to ground through the right hand windings of relays 312 and 313. It is to be noted that the batteries at the respective ends of the trunk circuit are now connected in opposition and therefore relay 312 associated with the outgoing end of the trunk circuit becomes currentless and deenergizes, opening at its armature and front contact the locking circuit previously traced through the relay 306 which relay thereupon deenergizes opening the circuit of relay 311. The trunk circuit is now restored to normal position.

The relay 312 is so wound as to release upon eight volts difference of potential between batteries at the respective ends of the toll trunk. If, however, there is a substantial difference in ground potential between the opposite ends of the trunk circuit, relay 312 may fail to release when the toll operator disconnects from the distant end of the toll trunk, and therefore relay 311 may be maintained energized to maintain a busy ground potential on the multiple test terminals of the trunk circuit appearing in the banks of district selectors in the office X , preventing the seizure of the trunk circuit

for a new connection even after the trunk circuit has been freed for use at both of its ends. To obviate such a false condition, differential relay 313 is provided, which relay will not operate under ordinary conditions, but will operate if there is such a difference of ground potential between the respective ends of the trunk circuit as will prevent the release of relay 312. When relay 313 energizes under such conditions, upon the disconnection of the toll operator's cord circuit from the distant end of the toll trunk, the holding circuit of relay 306 is opened at the armature and back contact of relay 313, thereby permitting the release of relay 311 and the disconnection of busy potential from the sleeve conductor 305 of the toll trunk.

If the toll operator at the toll switching center, is the first to disconnect from the toll trunk, the release of the connection proceeds in the following manner: Upon the withdrawal of plug P' from the jack J' , relay 315 deenergizes thereby connecting the windings of relay 314 to the conductors 307 and 308 of the toll trunk and since, at this time, the special operator has not pulled down the connection at her position and the switching relay 301 is energized over a circuit extending over the sleeve conductor 305, the relay 314 is therefore connected in a circuit in series with the supervisory relay 263 at the special operator's position. The supervisory relay 263 energizes in this circuit and closes a circuit for the supervisory lamp 231, which may be traced from grounded battery through lamp 231, the right hand armature and front contact of relay 266 and thence to ground through the armature and front contact to relay 263. When the subscriber A restores his receiver to its switchhook, the supervisory lamp 233 is illuminated in the manner previously described, and the operator noting the illumination of the supervisory lamps 231 and 233, proceeds to withdraw the plug P from the jack J , and the apparatus in the office X which was employed in the establishment of the connection, is restored in the manner previously described. When the selector switch 222 restores and moves its brushes from the terminals of the selected trunk circuit, the circuit of sleeve relay 304 of the toll trunk is opened, and this relay becomes deenergized opening the circuit of switching relay 301 and the circuit of relay 306. Upon the deenergization of switching relay 301 and the connection of the windings of relays 312 and 313 to the conductors 307 and 308 of the trunk circuit, the relays 312 and 313 do not energize since at this time the operator at the toll switching center has disconnected and there is no direct bridge across the incoming end of the trunk circuit for providing an operating circuit for relays 312 and 313.

115
120
125

Therefore, there is at this time, no holding circuit for relay 306 and this relay deenergizes opening the circuit of relay 311 which in turn removes busy potential from the sleeve conductor 305 of the trunk circuit.

If the calling subscriber abandons the call prior to the establishment of a toll connection with the selected toll trunk, that is, when the sequence switch 200 is in positions 2 to 9, the apparatus is restored in the following manner: upon restoration of the subscriber's receiver to the switchhook, supervisory relay 234 becomes deenergized thereby opening the locking circuit of relay 229, and closing a circuit for illuminating supervisory lamp 233. In response to the lamp signal, the operator withdraws plug P from jack J thereby opening the circuit of sleeve relay 223. A circuit is now closed for relay 238 which may be traced from grounded battery through the winding of relay 238, the upper left hand contact of sequence switch cam 219 (2 to 9), the upper armature and back contact of relay 223, and thence to ground at the right hand armature and back contact of relay 229. Relay 238, upon energizing, locks up to ground at cam 202, opens the fundamental circuit at its outer right hand armature and back contact, and at its left hand armature and front contact closes a circuit for driving the sequence switch 200 into position 10. This circuit may be traced from grounded battery, through the winding of the driving magnet of the sequence switch 200, the lower right hand contact of sequence switch cam 220 and thence to ground at the left hand armature and front contact of relay 238. Upon reaching position 10, a circuit is established for the down-drive magnet of selector switch 222 which may be traced from grounded battery, through the winding of magnet 270, the upper right hand contact of sequence switch cam 220 and thence to ground at the left hand armature and front contact of relay 238.

When the down-drive magnet 270 has restored the switch shaft to its normal position, a circuit is closed for driving the sequence switch 200 out of position 10 and into normal position, this circuit extending from grounded battery, through the winding of the driving magnet of sequence switch 200, the upper right hand contact of sequence switch cam 205, normal commutator segment 271, shaft wiper 276 and thence to ground through the lower left hand contact of sequence switch cam 202.

Should a selector switch fail to find an idle trunk circuit in the selected group during its trunk hunting movement when the sequence switch associated therewith is in position 8, a flashing signal will be

given to the special operator in the following manner: as soon as the set of tripped brushes move upwardly beyond the set of terminals in the selected group, the line relay 236 which was locked up so long as test brush 249 encountered terminals of busy trunks, deenergizes, and at its right hand armature and back contact, closes a circuit for driving the sequence switch out of position 8 and into position 9, this circuit extending from grounded battery, through the winding of the magnet of sequence switch 200, the lower left hand contact of sequence switch cam 209 (8) and thence to ground at the right hand armature and back contact of relay 236. Upon reaching position 9, the sequence switch is advanced in the manner hereinbefore described, by the sender into position 10. Since now the shaft wiper 243 is standing upon the conducting portion of the commutator 272, a circuit is now established for driving the sequence switch into position 11, this circuit may be traced from grounded battery, through the winding of the driving magnet of sequence switch 200, the lower left hand contact of sequence switch cam 205, segment 272, brush 243 and thence to ground through the lower left hand contact of sequence switch cam 202. In position 11, a circuit is established from ground on the segment 272 as previously traced, through the lower contacts of sequence switch cam 206 and thence through the left hand winding of relay 236 to grounded battery. Relay 236 energizes in this circuit and closes a locking circuit for itself extending from grounded battery through its left hand winding, its inner left hand armature and front contact, the upper left hand and lower right hand contacts of sequence switch cam 206 and thence to ground through segment 272 as previously traced. Relay 236 remains energized through position 15 of the sequence switch and closes at its right hand armature and front contact a circuit for driving the sequence switch into position 16. This circuit may be traced from grounded battery through the winding of the driving magnet of sequence switch 200, the left hand contacts of sequence switch cam 208 and thence to ground at the right hand armature and front contact of relay 236. When the sequence switch reaches position 16, a circuit is closed for flashing the supervisory lamp 231, which may be traced from grounded battery, through the lamp 231, the upper contacts of sequence switch cam 218 and thence to ground through the interrupter 273.

The operator, in response to the flashing signal, may then listen in on the connection in the manner previously described and inform the calling subscriber that there are

no idle toll trunks available for use at that time. The connection may then be restored in the manner previously described.

While in the foregoing description, the 5 special toll trunk shown in Fig. 3 has been described as employed in connection with a selector switch at the special operator's position for seizing its out-going end, it will be apparent to those skilled in the art that the 10 trunk circuit might readily be adapted to be employed in a manual exchange and seized at its outgoing end by manual means

What is claimed is:

1. In a telephone exchange system, an 15 originating office, a distant office, a trunk line extending between said offices, means at said first office for seizing said trunk line, means at said second office for extending a connection from said trunk line, a relay at the 20 outgoing end of said trunk line responsive to the seizure thereof, means controlled by said relay and effective upon the release of said trunk line at its outgoing end, for rendering said trunk line busy at its outgoing 25 end, and means controlled over said trunk line and effective upon the seizure of said trunk line and the subsequent release thereof, for maintaining said relay energized until connection with said trunk line has 30 been disestablished at said distant office.

2. In a telephone exchange system, an originating office, a distant office, a trunk line comprising two conductors only extending between said offices, means at said first office for seizing said trunk line, means at said second office for extending a connection from said trunk line, a relay at the outgoing end of said trunk line responsive to the seizure thereof, means controlled by said relay 35 and effective upon the release of said trunk line at its outgoing end for rendering said trunk line busy at its outgoing end, and means controlled over the conductors of said trunk line in series and effective upon the 40 seizure of said trunk line and the subsequent release thereof for maintaining said relay energized until connection with said trunk line has been disestablished at said distant office.

3. In a telephone exchange system, an originating office, a distant office, a trunk line comprising two conductors only extending between said offices, means at said first office for seizing said trunk line, means at said second office for extending a connection from said trunk line, a relay at the outgoing end of said trunk line responsive to the seizure thereof, means controlled by said relay and effective upon the release of said trunk line at its outgoing end for rendering said trunk line busy at its outgoing end, and a double wound relay controllable over the conductors of said trunk line in series and energized upon the seizure of said trunk line

and the subsequent release thereof for maintaining said first-named relay energized until connection with said trunk line has been disestablished at said distant office.

4. In a telephone exchange system, an originating office, a distant office, a trunk line comprising two conductors only, extending between said offices, means at said first office for seizing said trunk line, means at said second office for extending a connection from said trunk line, a relay at the outgoing end of said trunk line responsive to the seizure thereof, means controlled by said relay and effective upon the release of said trunk line at its outgoing end for rendering said trunk line busy at its outgoing end, a relay controlled over the conductors of said trunk line in series and effective upon the seizure of said trunk line and the subsequent release thereof for maintaining said first relay energized until connection with said trunk line has been disestablished at said distant office, and a differential relay also controlled over said trunk line for causing the release of said first-named relay upon failure of said second-named relay to 90 release the first-named relay upon the disestablishment of the connection at said distant office.

5. In a telephone exchange system, an originating office, a distant office, a trunk line extending between said offices, means at said first office for seizing said trunk line, means at said second office for extending a connection from said trunk line, a relay at the outgoing end of said trunk line responsive to the seizure thereof, means controlled by said relay and effective upon the release of the outgoing end of said trunk line for rendering said trunk line busy at its outgoing end, means controlled over said trunk line and effective upon the seizure and the subsequent release of said trunk line for establishing a holding circuit for said relay until connection with said trunk line is disestablished at said second office, and a differential relay operable over said trunk line for opening said holding circuit upon release of said trunk line at said second office when the difference of ground potential between said offices is sufficient to prevent the 110 release of said last-named means.

6. In a telephone exchange system, an originating office, a distant office, a trunk line extending between said offices, means at said first office for seizing said trunk line, means at said second office for extending a connection from said trunk line, a relay at the outgoing end of said trunk line responsive to the seizure thereof, means controlled by said relay and effective upon the release of the outgoing end of said trunk line for rendering said trunk line busy at its outgoing end, a double wound relay and a dif-

ferential relay associated with the outgoing end of said trunk line, and means effective upon the operation of said first-named relay and the subsequent release of said trunk line 5 at its outgoing end for connecting said latter relays with said trunk line whereby said double wound relay is energized over said trunk line to establish a holding circuit for said first-named relay until said trunk 10 line is released at said second office and whereby said differential relay is energized over said trunk line following the release of said trunk line at said second office to open said holding circuit when the difference of 15 ground potential between said offices is sufficient to prevent the release of said double wound relay.

7. In a telephone exchange system, an originating office, a distant office, a trunk 20 line extending between said offices, means at said first office for seizing said trunk line, means at said second office for extending a connection from said trunk line, a relay and a source of current associated with each end 25 of said trunk line, and means associated with each end of said trunk line and effective upon the release of the respective ends of said trunk line for bridging the respective relays and sources of current across said 30 trunk line whereby when said trunk line is free at each of its ends, said relays are connected in opposition over said trunk line.

8. In a telephone exchange system, an originating office, a distant office, a trunk 35 line extending between said offices, a relay and a source of current at each office adapted to be connected in bridge with the respective ends of said trunk line in such a manner as to be in opposition when both of said 40 relays are connected to said trunk line, and a differential relay associated with one end of said trunk line and adapted to be operated over said trunk line when a difference of ground potential exists between the respective ends of said trunk line.

9. In a telephone exchange system, an originating office, a distant office, a trunk line extending between said offices, means at said first office for seizing said trunk line, 50 a cord circuit at said second office for extending a connection from said trunk line, a line relay normally bridged across said trunk line at said second office, a cutoff relay energized upon connection with said 55 trunk line for disconnecting said line relay from said trunk line, a flashing relay adapted to be bridged across said trunk line upon the energization of said cutoff relay, a 60 flashing key at said first office for intermittently energizing said flashing relay, and a supervisory signal associated with said cord

circuit and under the control of said flashing relay.

10. In a telephone exchange system, an originating office, a distant office, a trunk 65 line extending between said offices, means at said first office for seizing said trunk line, a cord circuit at said second office for extending a connection from said trunk line, a line relay normally bridged across said 70 trunk line at said second office, a cutoff relay energized over the sleeve conductor of said cord circuit upon connection with said trunk line for disconnecting said line relay from said trunk line, a flashing relay adapted 75 to be bridged across said trunk line upon the energization of said cutoff relay, a flashing key at said first office for intermittently energizing said flashing relay, a supervisory 80 signal associated with said cord circuit, and means controlled by said flashing relay for increasing the flow of current in said sleeve conductor to operate said signal.

11. The combination of a telephone line, supervisory apparatus connected thereto at 85 separated points and subject to difference of ground potentials, with compensating means operative over said line and responsive to said difference of potential for preventing said difference of potential from improperly 90 affecting said apparatus.

12. The combination of a telephone line, and supervisory apparatus connected thereto at separated points and subject to difference of ground potentials, with automatic controlling means for said apparatus operative over said line and responsive to said difference of potential.

13. In a telephone exchange system a first operator's position, a second operator's position, a trunk circuit extending between said positions, a signal at the second operator's position, a link circuit at the first and a link circuit at the second operator's position, a supervisory signal for each of 100 said link circuits, means responsive to the connection of the link circuit at said first position with said trunk circuit for actuating said first signal, means responsive to the connection of the link circuit at said second position with said trunk circuit for extinguishing said signal and means responsive to the disconnection of the link circuit at 105 said first position for operating the supervisory signal of said link circuit at said second position and for rendering said trunk circuit busy until the link circuit at said second position is disconnected.

In witness whereof, I hereunto subscribe my name this 14th day of October, A. D. 120 1920.

JOHN W. GOODERHAM.
